MULTICHANNEL CARRIER COMMUNICATION SYSTEM

Kenneth George Hodgson and Frank Fairley, London, England, assignors to International Standard Electric Corporation, New York, N. Y.

Application May 23, 1947, Serial No. 750,148
In Great Britain April 8, 1946

Section 1, Public Law 690, August 8, 1946
Patent expires April 8, 1966

2 Claims. (Cl. 178—50)

1

The present invention relates to multi-channel signalling systems.

In connection with such a system, which comprises a plurality of channels—say α channels—of equal or approximately equal frequency spacing, it is known to derive each of a number—say β —of groups of n channels by a first modulation process, so that $\alpha = n\beta$, each group of channels occupying the same primary frequency range, and subsequently to translate, by means of a second modulation process, the groups to their final different positions within the frequency range to be transmitted. If the primary frequency range lies within the frequency range which is finally transmitted, one group, hereinafter called the "basic group" may be used without a second modulation process, and this group is not necessarily the lowest group in the frequency range to be transmitted as will be made clear in the following. In this case, however, it is difficult to avoid interference between the basic group and the groups immediately adjacent to the basic group. The reason for this interference is that the output of the second modulator contains the wanted and unwanted sidebands and also the input frequencies which lie in the frequency range of the basic group. In most of the groups the unwanted sidebands and the input frequencies can easily be eliminated by filters, but in the groups adjacent to the basic group the frequency space between the wanted sideband and the band in which the input frequencies lie is so small that filters have to be used of an extremely sharp cut-off characteristic in order to eliminate the input band without introducing distortion into the wanted sideband. Even if the modulators are balanced to reduce the transmission of the input frequency, the filter requirements are very difficult to meet. In order to overcome this difficulty, one could provide a frequency gap between the basic group and the adjacent groups. This, however, would reduce the number α of transmission channels within the available total frequency range.

It is an object of the invention to provide a multi-channel signalling system which overcomes these difficulties without the necessity of providing substantial frequency gaps within the total frequency range of transmission.

A multi-channel signalling system, according to the invention, employs a basic group of channels occupying a primary frequency range, other groups of channels each occupying the whole or part of the primary frequency range, and comprising means for translating such other groups

2

to frequency ranges outside the primary frequency range and is characterised in this that groups of channels which are translated to occupy positions in the frequency range adjacent to the primary frequency range have bandwidths which are less than the whole bandwidth of the primary frequency range.

To make the invention more clearly understood, reference will now be made to the accompanying drawings, which are given by way of example only and in which:

Figs. 1 and 2 serve to illustrate the underlying principle of the invention;

Figs. 3 and 4 illustrate arrangements of known 15 multi-channel alternating current telegraph systems;

Figs. 5, 6, and 7 serve to illustrate the principle of the invention as applied to the arrangement shown in Fig. 4.

20 Referring first to Fig. 1, the arrow 1 indicates a basic group of n channels in the primary frequency range from f_1 to f_2 . The arrow 2 indicates another group of $n-x$ channels, extending from the frequency f_1 to f_3 . By modulating this 25 other group with the frequency (f_2+f_3) , as indicated at 3, and employing the lower sideband only, the said other group is translated to assume a frequency range extending from f_2 to $(f_2+f_3-f_1)$, as indicated at 4. It will be seen 30 that an uninterrupted frequency range is utilised without any substantial gap, that is to say, the frequency range from f_1 to f_2 is occupied by the basic group 1 and the range from f_2 to $(f_2+f_3-f_1)$ is occupied by said other group after 35 it has been translated to the position 4 (the groups 1 and 4 which are actually transmitted being indicated by arrows in full lines), while yet the requirements on the design of filters are considerably eased since the separation of the 40 frequencies between f_3 and f_2 from the band 4 after the process of modulating the band 2 with the carrier 3 is not critical; in other words, the frequency gap between the input band 2 and the translated band 4 allows the filter attenuation 45 to rise to a value necessary to eliminate the input frequency band 2 from the translated band 4, so that the input band 2 can no longer interfere with the band 1.

If the total frequency band available for transmission extends to lower frequencies beyond f_1 , a third group 5 of $n-y$ channels, extending from the frequency f_4 to the frequency f_2 , may be modulated by the frequency (f_4+f_1) indicated at 7, whereby the group, by using the lower sideband, is translated to the frequency band 6, ex-

tending from f_1 to $(f_4 + f_1 - f_2)$. It will, again, be realised that a frequency gap extending from f_1 to f_4 exists between the input frequency band 5 and the translated band 6 which is being transmitted. Again, this gap is sufficient to allow the filter attenuation to rise to a value necessary to eliminate the input frequency band 5, while the transmitted band 6 is adjacent to the basic band 1, without leaving any gap in the frequency range to be transmitted.

The transmitted groups of frequency bands are now 1, 4, and 6 (indicated by arrows in full lines) and cover an uninterrupted frequency range.

In the example illustrated, in Fig. 1 the groups 4 and 6, adjacent to the basic group 1, each comprise fewer channels than the basic group 1. If it is desired to transmit groups of channels of equal widths, the system so far described may be modified as will now be explained with reference to Fig. 2. In Fig. 2, the basic group of n channels is again indicated by the arrow 1. Another group of n channels, which eventually occupies the upper frequency range adjacent to the basic range 1, is broken up so as to form two sub-groups, one comprising $n-x$ channels and extending from frequency f_1 to f_3 as indicated at 2, and the other comprising x channels and extending from f_3 to f_2 as indicated at 10. The frequencies of the sub-group 2 are modulated by the frequency $(f_2 + f_3)$ as indicated at 3, and the sub-group 10 is modulated by the frequency $(2f_2 + f_3 - f_1)$ as indicated at 11. If lower sidebands are used, the sub-group 1 is translated to assume the final position 4 as in Fig. 1, and the sub-group 10 is translated to assume the final position 12. It will be seen that the groups 1, 4 and 12 occupy an uninterrupted frequency range, while sufficient gaps exist between the translated group 4 and the input group 2 on the one hand and the translated group 12 and the input group 10 on the other, for easing the filter design.

A third group of n channels may be broken up into two sub-groups 13 and 14 comprising respectively $n-y$ and y channels, and extending from f_4 to f_2 and from f_1 to f_4 respectively. The group 13 is modulated by the frequency $(f_4 + f_1)$ as indicated at 15, and the group 14 by the frequency $(2f_1 + f_4 - f_2)$ as indicated at 16. If, again, lower sidebands are used, the sub-groups 13 and 14 are translated respectively to the positions 17 and 18, extending from $(f_1 + f_4 - f_2)$ to f_1 and from $(2f_1 - f_2)$ to $(f_1 + f_4 - f_2)$. Again, it will be appreciated that the groups 18, 17, 1, 4, and 12 (indicated by arrows in full lines) occupy an uninterrupted frequency range available for transmission without any substantial gap, while gaps exist between each input group and the corresponding translated group whereby each input group may be suppressed from the translated group without raising unduly the requirements of the filters.

In the examples so far described, only the lower side bands are employed and the upper sidebands suppressed, and the frequency with which a group of channels is modulated is the sum of the frequencies representing one boundary of the group that is to be translated, and the corresponding boundary of the translated group. This means, it will be seen, that when a boundary of the translated group is the same as one boundary of the basic group the group before translation occupies a part of the frequency range of the basic group and the carrier frequency used for translation is the sum of the frequencies at either end of the gap between the two frequency ranges.

It is, however, possible to use upper sidebands in the translating operation and suppress the lower sidebands, the modulating frequency used for the translation being the difference of the two boundary frequencies of the basic group. Since the modulating frequency in this latter case would be comparatively low, it is usually preferable to employ the lower sidebands.

The principle of the invention may be used in connection with multiple channel carrier telephony and with multi-channel voice frequency telegraphy. It is also obvious that the invention is not restricted to systems using two subsequent modulations but may with equal advantage be used in connection with systems using more than two such modulations.

Applications of the invention to multi-channel voice frequency telegraph systems will now be described. Fig. 3 diagrammatically illustrates such a system of known type arranged for unidirectional operation. For the reverse direction, the same frequencies are used along a second communication channel with equipment at the sending and the receiving ends similar to those indicated in Fig. 3. At the transmitting side, the equipment for one channel comprises a telegraph modulator M_1 for modulating a frequency f_1 with direct current telegraph signals, a bandpass filter BF_1 which transmits the frequency f_1 with the telegraph sidebands, and at the receiving side a bandpass filter BF_1 and a detector D_1 for converting the alternating current signals for operating the telegraph equipment, the transmitting and receiving sides being connected by any suitable transmission path such as a cable. The equipment for the channels 2, 3 . . . n is similar to that of channel 1, the output of all the transmitting bandpass filters being connected in parallel to one another and to the line, and likewise the inputs of all the receiving bandpass filters being connected in parallel to one another and to the line. With such a system it is usual to choose the frequencies f_1 to f_n , so that they are odd harmonics of a single fundamental frequency. Thus, the telegraph channels are spaced uniformly in the total frequency range available for transmission. Fig. 5 represents the attenuation frequency characteristics of the sending or receiving band filters BF_1 to BF_n .

The design of the filters BF_1 to BF_n becomes increasingly difficult as the frequency increases. For example, in practice it has been possible to arrange the frequencies f_1 to f_n at a spacing of 120 C. P. S. within the frequency range 420 to 2460 C. P. S. the latter being close to the upper limit (2500 C. P. S.) of the band width that has been heretofore used for telephony. Wider bandwidths, up to 3600 C. P. S. are now, however, being introduced to an increasing extent and it is desirable, if one of the channels of a multiplex carrier telephone system is to be allotted for the provision of a multiplex voice frequency telegraph system, that the bandwidth available should be fully occupied by telegraph channels. The extension of the upper frequency range of known systems means increasing difficulty in filter design to the point of impracticability if the existing channel spacing is to be retained. The obvious remedy would be to depart from the uniform spacing of the signal channels and to increase the frequency spacing in the upper frequency range available for transmission. This, however, would prevent the derivation from a single fundamental frequency of all the frequencies f_1 to f_n unless the spacing is increased by the width of a chan-

nel or a multiple thereof, which would considerably reduce the number of channels otherwise available for transmission. This difficulty is overcome by means of the present invention.

In the arrangement shown in Fig. 4, a basic group of n channels is derived by direct modulation by means of modulators $M^1 \dots M^n$ and bandpass filters $BF^1 \dots BF^n$, the modulated frequencies being demodulated by detectors $D^1 \dots D^n$. Another group of n channels is derived by modulators $M^{11} \dots M^{1n}$ and bandpass filters $BF^{11} \dots BF^{1n}$ and a second modulation of channel frequencies f^1 to f^n by means of group modulator GM using a carrier frequency fx . GBF represents a group band filter and P represents coupling means to separate the basic group of channels from the other group of channels. At the receiving end, similar coupling means P separate the basic group of channels from the group modulated channels, which pass through the group band filter GBF to the group demodulator GDM using the same carrier frequency fx . The system so far described is also known.

Fig. 6 shows the attenuation frequency characteristics of the band filters BF^1 to BF^n and the characteristic of the group band filters GBF . The vertical characteristics of the band filters BF^{11} to BF^{1n} when group modulated and shifted in the frequency range by the frequency fx are shown in dotted lines. The requirements of the group band filter GBF at the sending end are that this filter shall pass one set of sidebands derived from modulation of frequencies f^1 to f^n by the carrier frequency fx with a minimum attenuation, whereas it shall attenuate the input frequencies f^1 to f^n sufficiently to avoid interference between the said input frequencies and the primary frequencies f^1 to f^n of the basic group of channels which have not undergone a second modulation. At the receiving end the requirements of this filter are similar. It is difficult or impossible to design a filter to achieve this purpose without allowing a gap within the frequency range actually transmitted between the channel n of the basic group of channels and the adjacent channel of the group modulated channels, and at least one or possibly two such channels would be lost in the frequency spectrum available for transmission.

The invention is applied as shown in Fig. 7. As in Fig. 6 a basic group is derived by direct modulation by means of modulators $M^1 \dots M^n$ and band pass filters $BF^1 \dots BF^n$. A second group of channels f^1 to f^n , where f^m is lower than f^n is derived by modulators $M^{11} \dots M^{1m}$ and band pass filters $BF^{11} \dots BF^{1m}$. This group is then translated to the position in the frequency spectrum adjacent to the basic group by a second modulation by means of group modulator GM using a carrier frequency $fx=f^n+f^m$. The group band filter GBF is used to select the lower sideband and to suppress the carrier frequency and the upper sideband. The lower sideband is applied to the line through a coupling device P such as a hybrid coil.

A similar result would be obtained by using for the carrier supplied to the modulator GM , a frequency of f^n-f^1 , and selecting the upper sideband by the filter GBF . As stated above, however, it is preferred to use the lower sideband.

The requirements of the group band filter GBF are illustrated in Fig. 8, from which it may be seen that it is now permissible for the frequencies between $f^{(m+1)}$ and f^n of the basic group which are not group modulated to lie within the pass

range of GBF without suffering interference from the group modulated channels, thus allowing uniform spacing of the frequencies throughout the frequency range available for transmission by choosing $fx=f^m+f^n$ and using the lower sideband. The same argument is valid for the receiving end where frequencies between $f^{(m+1)}$ and f^n are accepted by the receiving group band filter GBF but are not accepted by the receiving band filters BF^{11} to BF^{1m} after demodulation.

If the line between transmitting and receiving stations is capable of transmitting frequencies as high as $2fn$, then a number of channels equal to $n-m$ are formed by modulation in modulators $M^{1(m+1)}$ to M^{1n} by carrier frequencies $f^{(m+1)}$ to f^m . This sub-group is group modulated in group modulator G^1M with a frequency $fy=2fn+f^m-f^1$, the lower sideband is selected by a filter GBF^1 and applied to the line through a coupling device P^1 separating this sub-group from the basic group and the side-band passing the filter GBF . It will be seen from the foregoing description of Fig. 2, that the actually transmitted frequency range is uninterrupted and yet the requirements of the filters are considerably eased. Furthermore, it is possible to have a basic group of channels derived directly from primary frequencies f^1 to f^n , another group of channels derived from input frequencies f^1 to f^m where f^m is less than f^n by a single group modulation as described whereby a block of channels of total number $n+m$ is obtained. Similarly, a second block of channels of total number $n+p$ may be obtained wherein f^p is less than f^n and the two blocks may be combined with each other in accordance with this invention so as to result in a uniform channel frequency spacing on the transmission line throughout the range of frequencies which are passed by the line.

Furthermore, the means by which a group or groups of channels is or are translated to positions in the frequency spectrum below the basic group will be clear. From the foregoing and from a comparison with Figs. 1 and 2, the only alteration necessary being in the choice of carrier frequency to be used in the group modulator or modulators. It is also clear that, although the invention has been illustrated as applied to telegraph channels it is equally applicable to carrier telephone or other communication channels systems.

What is claimed is:

1. A multi-channel signalling system comprising modulating means and filter means for creating a basic group of channels occupying a primary frequency range and impressing said group on a transmission line, modulating means and filter means for creating another group of channels occupying a part of said frequency range from one boundary thereof to an intermediate frequency, group modulating means for modulating said other group of channels with a frequency equal to the sum of said intermediate frequency and the frequency of the other boundary of said range, filter means for selecting the lower side band from the output of said group modulating means and means for impressing said lower side band on said line.
2. A multi-channel signalling system comprising modulating means and filter means for creating a basic group of channels occupying a primary frequency range and impressing said group on a transmission line, modulating means and filter means for creating another group of chan-

nels occupying a part of said frequency range from one boundary thereof to an intermediate frequency, group modulating means for modulating said other group of channels with a frequency equal to the difference between said boundaries of said primary frequency range, filter means for selecting the upper sideband from the output of said group modulating means, and means for impressing said upper sideband on said line.
